RAIL JOINT

Robert F. Bolam, Tampa, Fla.

Application August 21, 1935, Serial No. 37,221

1 Claim. (Cl. 238—187)

This invention relates to a rail joint and it aims to provide an exceedingly strong and efficient construction.

More specifically, it is aimed to provide a construction utilizing a plate or chair of channel shape in cross section adapted to be spiked to the ties, and in turn to support the ends of the adjacent rails, in combination with a novel sliding or wedge plate and a locking plate having toothed connections with the wedge plate.

The more specific objects and advantages will become apparent from a consideration of the description following taken in connection with the accompanying drawings illustrating an operative embodiment.

In said drawings:—

Figure 1 is a side elevation showing the joint applied to rails and in the process of application;

Figure 2 is a side elevation of the reverse side of the joint and rails of Figure 1;

Figure 3 is a plan view of the joint and rails;

Figure 4 is a cross sectional view taken on the line 4—4 of Figure 2;

Figure 5 is a longitudinal sectional view taken on the line 5—5 of Figure 2;

Figure 6 is a cross sectional view taken on the line 6—6 of Figure 2;

Figure 7 is a cross sectional view taken on the line 7—7 of Figure 2;

Figure 8 is a cross sectional view taken on the line 8—8 of Figure 1;

Figure 9 is a fragmentary perspective view of a part of the rail joint and

Figure 10 is a front elevation of the locking member.

Referring specifically to the drawings, the improved construction consists of a one piece chair or plate 10 adapted to be secured to the ordinary ties 11 as by means of spikes 12 driven into the same and in turn directly engaging lugs 13 on such chair. Such plate or chair 10 is generally of channel shape in cross section but centrally has a web 14 and tread or ball 15, corresponding to such parts on the usual rails which are generally designated 16. The channel-shaped portions of the chair are thus at opposite ends thereof and along one side have L-shaped flanges 17 to overlap the base flanges of the rails 16 and at the opposite side have flanges 18 which overlap not only the base flanges but extend vertically the height of the web 14 so that the tread flanges will rest thereon. At the lower end of the web 14 is a base flange 19 integral therewith and also

integral with the base, corresponding with the base flanges of the rails 16.

The distance between said flanges 17 and 18 is much greater than the width of the base flange of the rail so that the chair 10 may be applied to the rails, before fastening to the ties, by angular disposition of the chair with respect to the rails and then turning the chair relatively to the rails substantially on a longitudinal axis of the rails, the portions 14, 15, and 19, thus being between 10 the rails and in effect forming a continuation thereof. In addition, through the aforesaid movement, lugs 20 on the flange 18, extend into openings 21 in the webs of the rails 16.

In order to secure the rails within the chair 10, a slideable bar 22 is employed which intimately engages the inner surface of the flange 17 and intimately engages the base flanges of the rails, flange 19, the webs of the rails, web 14, and under surface of the tread flanges of the rails and said flange 15, the latter having a depending flange 23 which overlaps the bar 22.

It will be noted that said slideable bar 22 has rack teeth at 24 and adjacent the same, in portion 25 which engages the rail web, has a horizontally elongated slot 26 and in registry therewith, the web 14 has an opening 27 therethrough. The base flange 19 also has integral with it and integral with the flange 17, an enlargement 28 provided with a concaved bearing surface 29. As a result, as best shown in Figures 1 and 8, a shaft 30 may be removably journaled in the opening 27. Shaft 30 carries a pinion 31 which meshes with the rack teeth 24. The opposite end of shaft 30 is polygonal as at 32 and removably engaged by the corresponding opening in a lever 33. As a result, through turning of the lever, which may be of the ratchet type, a pinion 31 will slide the slide bar 22 into operative position, after which the shaft 30, pinion 31 and lever 33 may be removed, the depression 29 affording clearance for the removal of the pinion. It will be clear, that in some instances, slide bar 22 may be driven in place from one end. Said slide bar, 45 also, if desired may be of wedge shape in cross section, and the surfaces engaged thereby similarly inclined.

After the positioning of the slide bar 22, a locking bar 34 as detailed in Figure 10 is applied, such bar occupying most of the slot 26, as best shown in Figure 5 and having portions 35 overlapping the webs of the rails and engaging the under surfaces of their tread flanges. Between such portions 35, a slot 36 is provided which interlocks 55

with the tread 15 and flange 23. Said locking member also has rack teeth 37 which interfit the rack teeth 24 and since a screw stem 38 extends rigidly from the fastening member through the opening 27 and receives a washer and nut 39 and 40 on the reverse side of the chair, the parts are effectively fastened in position.

It will be realized that the construction is applicable to rails without disturbing the spikes which directly secure the rails to ties, since the rails do not have to be moved longitudinally one relatively to the other. Additional strength is afforded as well as an increase in the spring cushioning or resilient action to offset the shock encountered in use.

In addition to the nut 40, it is clear that a permutation lock may also be used to prevent tampering with the parts. It will be realized that the various angles employed support each other under stress and strain, that the parts may be readily cast in the process of manufacture, and that there is due allowance for expansion and contraction under climatic conditions.

Various changes may be resorted to provided they fall within the spirit and scope of the invention.

What is claimed is:—

A rail joint comprising a chair having an intermediate portion of rail shape adapted to be abutted by the rails, portions of channel shape receiving the rails on opposite sides of said intermediate portion, a sliding bar to fasten the chair and rails together held in place by the chair engaging the first-mentioned portion and being disposed in each of said channel-shaped portions, fastening means passing through said intermediate portion having a locking member engaging said bar, said bar having a slot, said fastening means passing through said slot, interengaging teeth between said locking member and said bar, and a flange on the intermediate portion interengaged with said locking member.
